INVENTOR:

JOHN O. ERICKSON,
BY: Otto de Kruge,
his Atty.

UNITED STATES PATENT OFFICE.

JOHN O. ERICKSON, OF LOS ANGELES, CALIFORNIA.

HOOK.

Application filed December 15, 1921. Serial No. 522,604.

To all whom it may concern:

Be it known that I, JOHN O. ERICKSON, a citizen of the United States, residing at Los Angeles, in the county of Los Angeles and 5 State of California, have invented a new and useful Hook, of which the following is a specification.

This invention relates to devices applied to walls, boards, mouldings, or shelves, for 10 hanging clothes, and other wearing apparel.

One of the objects of this invention is to provide a device which can easily be carried in the pocket and applied to a convenient place for supporting wearing apparel.

15 Another object is to provide a device which can be applied without the use of screws, nails, or similar means.

Another object is to provide a device which, in emergency cases, may be applied in 20 rooms and at places where such a device is otherwise not desirable, and which may easily be removed without disfiguring walls or places to which it has been attached.

Other objects will appear from the following description and appended claim as well 25 as from the accompanying drawing, in which—

The figure is a perspective view of a form 30 of a clothes hook, embodying the invention, a board being indicated in dotted lines to illustrate the manner in which this device is applied.

Mouldings, boards, shelves and similar 35 members in a house are of various sizes and shapes, and it will therefore easily be understood that the attaching portions of the device must also vary to quite an extent to make the device adaptable to the conditions in different places.

40 In the illustration in the drawing, the device is of a preferable form to be used for hanging clothes in closets, this device being made of a form to easily engage over a moulding or board to serve in a similar manner as common screwed-in clothes-hooks. The upper supporting hook-portion 1 extends rearwardly and terminates in an engaging or claw-like hook-portion, as indicated at 2. A loop 3 is formed, so that the 45 upper end of the spring 4 can be applied. An independent claw-like hook-portion 5 is engaged with the lower end 6 of the spring 4.

The member 7 of the upper hook-portion, and the members 8 and 9 in the lower hook-portion, as also the claw-like termination 10 55 of the member 9, are merely suitable continuations of the whole design of the hook proper in an agreeable and pleasing as well as a convenient construction of this form of the device, embodying the invention. The 60 front ends 11 and 12 of the upper and lower hook-portions of the hook proper are in this manner of a rounded form, so as not to catch so easily in the clothes and articles supported by the hook proper.

65 The claw-like engaging members 2 and 5, and the spring 4, can, of course, be made of various forms and shapes to suit the conditions of boards, mouldings, and other members to which the device may be applied, 70 without departing from the principle of this invention.

A workingman may easily carry a device of this form in his pocket and, at his place of employment, may apply the device to a 75 fence or the bark of a tree without much difficulty, as will easily be understood. Outing parties may use this device with similar advantage.

No screws, nails, or other similar means 80 are necessary for holding the device in position, so it may easily be removed without leaving any trace or disfiguring furniture or any part of a house when used in emergency cases at places or points where such a device 85 is normally not desirable.

Having thus described my invention, I claim:

In a clothes hook, a hook proper made of a single wire having upper and lower hook 90 portions projecting forwardly and having engaging claws projecting rearwardly near the highest point of the hook proper, a loop being formed by the wire near the claws, an engaging hook member, and a coil spring 95 operatively connecting the loop on the hook proper with the engaging hook member.

In testimony that I claim the foregoing as my invention I have signed my name in the presence of two subscribing witnesses.

JOHN O. ERICKSON.

Witnesses:

A. WILSTAM,
O. H. KRUEGER.
